UNITED STATES PATENT OFFICE.

OVERTON WINSTON, OF MINNEAPOLIS, MINNESOTA.

REFLECTOR FOR HEADLIGHTS.

Application filed May 3, 1920, Serial No. 378,481. Renewed May 18, 1923.

To all whom it may concern:

Be it known that I, OVERTON WINSTON, a citizen of the United States, residing at Minneapolis, in the county of Hennepin and 5 State of Minnesota, have invented certain new and useful Improvements in Reflectors for Headlights; and I do hereby declare the following to be a full, clear, and exact description of the invention, such as will 10 enable others skilled in the art to which it appertains to make and use the same:

My present invention relates to headlights, such as used on automobiles, and elsewhere, to give an approximately horizontal forward 15 projection of the light beam, and is directed to the provision of an improved reflector for such headlights, whereby an improved proportionate distribution of the light on and above the road is obtained.

20 The present invention is in part a modification of or improvement on the reflector disclosed and broadly claimed in my pending application, S. N. 112,683, filed of date, August 2nd, 1916, and entitled "Headlights".

25 The present invention is illustrated in the accompanying drawings wherein like characters indicate like parts throughout the several views.

Referring to the drawings:

30 Fig. 1 is a diagrammatic front elevation of the reflector;

Fig. 2 is a diagrammatic vertical section taken on the line 2—2 of Fig. 1;

35 Fig. 3 is a diagrammatic oblique section taken on either of the lines 3—3 or 3'—3' of Fig. 1;

Fig. 4 is a diagrammatic horizontal section taken on the line 4—4 of Fig. 1;

40 Fig. 5 is a diagrammatic view of the reflector in oblique projection;

Fig. 6 is a side elevation of an assumed cone on which one of the directing curves is shown;

45 Fig. 7 is an end elevation of the cone and directing curve shown in Fig. 6;

Fig. 8 is a development of the surface of the cone shown in Figs. 6 and 7.

The form of my present improved reflector may be made clear by assuming a reflector with a light source therein and by stating that the surface of said reflector may be 50 regarded as being generated by a conic revolved downwardly, in opposite directions, on the approximately horizontal axis of the conic, while continuously increasing, at the same time, both its radial distance from

said axis and the distance from said light source of its vertex or point of intersection with said axis. This produces a reflector, 60 the reflecting surface of which will be without offsets or broken surfaces, but in which the upper portion of the reflector will be much closer to said light source than will the lower portion of said reflector. In a horizontal section, the reflector is preferably bi-symmetrical, as shown in Fig. 4.

Referring now to Fig. 5, it should be noted that the vertical axial section of the reflector consists of two conics 2— x^1 and x^5 —2. The said conic 2— x^1 is the assumed initial 70 position of the generating conic, and the conic x^5 —2 is the assumed terminal position of the said generating conic; and here it should be noted, that during the semi-revolution from top to bottom, the vertex or point 75 of intersection of the generating conic with its axis y — y , continuously moves rearward from the most forward point x^1 to the most rearward point x^5 .

The conic at the horizontal axial section 80 of the reflector is represented by the curved line 4— x^3 —4; and here it will be noted that the vertex or point of intersection of said conic with axis y — y , at x^3 , is between the above noted points x^1 and x^5 .

The generating conic at the oblique axial section of the reflector, on the line 3—3, is represented by the curved lines 3— x^2 and x^4 —3.

90 Here it may be further stated that the conics 2— x^1 and x^5 —2 are the conics illustrated in Fig. 2; that the conic 4— x^3 —4 is the conic represented in Fig. 4; and that the conics 3— x^2 and x^4 —3 are the conics represented in Fig. 3. The conics 3'— x^2 and x^4 —3' are conics that correspond, respectively, to the conics 3— x^2 and x^4 —3 of Fig. 5, taken on the opposite oblique axial section from section 3—3.

95 Fig. 5 also clearly illustrates the already 100 stated fact that the generating conic, in revolving from its assumed initial or uppermost position 2— x^1 , to its terminal or lowermost position 2— x^5 , continuously increases, at the same time, both its radial distance 105 from its axis and the distance from said light source of its vertex or point of intersection with said axis, and successively passes through the upper oblique, horizontal, and lower oblique positions, diagrammatically 110 shown in Fig. 5; and this statement is true, regardless of, in which direction the said

generating conic is downwardly revolved on said axis.

It follows from statements already made, and from the illustrations in Fig. 5, and also 5 in Figs. 2, 3 and 4, that the axis $y-y$ of the reflector is the common axis of all of the conics' center a whose common focal center a is also clearly illustrated in Figs. 2, 3, 4 and 5.

10 From the foregoing description, it will be seen that, in the reflector illustrated, two progressions or variations are involved in the generation of the surface, to wit: one varying the distance between the focus and 15 the vertex, and the other increasing the radial distance from the axis of revolution as the generating conic revolves from its uppermost to its lowermost position. In the illustrated form of the reflector, the first 20 named progression is secured by moving the vertex rearward as the generating conic revolves downward, which is by far the best way of securing this variation, because it enables the light to be kept on the focus. 25 The progression of the vertex of the generating conic, along the line of the axis of revolution, of itself, produces a radial progression, inasmuch as the cross sections of the generated surface, thereby produced, 30 will not, generally speaking, be curves which are symmetrical, in respect to both the horizontal and vertical planes through the axis of revolution, due to the fact that the distance from the focus to the vertex is 35 changed by said progression of the vertex.

The peculiar contour of the above described reflector will necessarily distribute the reflected light in a manner radically different from the distribution secured from an 40 ordinary reflector, wherein the surface is simply one of revolution, regardless of which one of the three conics, ellipse, parabola, or hyperbola, may be used. In all of such ordinary reflectors, as is well known, 45 the surface normals are in radial planes and intersect the axis of revolution, and, consequently, the incident ray, the surface normal and the reflected ray are in one and the same radial plane; and the general result 50 is that there will be an equal amount of light reflected both above and below the horizontal plane of the axis of the reflector, when the light is located at the focus.

In practice, the reflector will usually have 55 an axial hole to accommodate a light bulb socket, which hole is not shown in the dia-grammatic drawings.

The peculiar contour of my reflectors (whether of the form described in said prior 60 application, or in the further improved form hereinafter more fully described) will have an entirely different effect in the distribution of the reflected light, from that of a symmetrical reflector, for the controlling 65 reason that any surface normal is necessa-

rily out of and under the radial plane passing through the point of intersection of said normal and surface of the reflector, and hence, it necessarily follows that all of the incident rays, which strike any portion of the reflector above the horizontal plane of its axis, will be reflected out of and under 70 their respective radial planes. The same principles, in respect to the surface normals and in respect to the reflected rays, of course, 75 apply to that portion of the reflector below the horizontal plane of its axis, and hence, the light source can be so adjusted that all reflected rays from that portion of the reflector below the horizontal plane of its axis 80 are deflected downwardly to a greater degree and strike the road nearer the reflector than rays reflected from the lower portion of the ordinary symmetrical reflector. In other words, in my improved and peculiar reflectors, all of the reflected light from the lower portion (to wit: that portion below the horizontal plane of the axis of the reflector) and a large part of the light from the upper portion (to wit: that portion above the said 85 horizontal axial plane) becomes available for illumination of the road.

Nevertheless, notwithstanding the truth of the foregoing statements, some of the incident rays, which strike the portion of the reflector above its horizontal axial plane, 90 will not be reflected downwardly to such a degree as to pass below the horizontal plane of the axis of the reflector, and will co-operate with the unreflected rays from the light source, to afford all of the light needed above the horizontal plane of the axis of the reflector.

The following are features which distinguish the present invention from my prior 105 invention, to wit:

The generating conic, while being revolved in a downward direction, as described, is guided by two predetermined 110 directing curves.

In a commercial reflector, there is no way of the manufacturer guaranteeing that a certain predetermined designed filament is to be used in the light bulb and that the consumer is going to always have the hot spot 115 of his filament at any one predetermined point, with the result that it will be impossible for the manufacturer to design a reflector and be assured that the reflector will be used as designed. As is well known, if the 120 light bulb is placed too far forward of the focus, then the bottom portion of the reflector will illuminate objects above the surface of the road, while the upper portion of the reflector will illuminate the roadway; 125 while if the light source is placed way back toward the vertex, then the tendency will be for the upper portion of the reflector to illuminate objects above the road and for the lower portion of the reflector to illuminate 130

the surface of the road. These variations of positions of the light source being due entirely to the consumer's inattention to the laws of the science of illumination, it is 5 easily seen that if the manufacturer designs a reflector in which the upper portion of the reflector is to illuminate objects above the road and the lower portion of the reflector is to illuminate the surface of the road, 10 which will necessitate the light source being at one predetermined position, if the consumer places his light source far ahead of the predetermined position, then, instead of the upper portion of the reflector illuminating objects above the road, it will illuminate the surface of the road with the result that the reflector will be used in a way in which it was not intended that it should be used.

20 It is now readily seen that a commercial reflector should be non-blinding, regardless of whether the light source is way back toward the vertex or way forward near the rim, consequently the geometrical characteristics of the lower half of the reflector must be the same as the geometrical characteristics of the upper half of the reflector, so that substantially the same illuminating result is produced, regardless of whether the 25 surface of the road, or an object above the road is illuminated by reflected light from either the upper or lower portion of the reflector.

A reflector as shown in the drawings of 30 the present application has a directing curve in a plane perpendicular to the axis $y-y$ of the reflector, with such geometrical characteristics that the normals to the surface of the reflector, at points on the lower half of the directing curve, are deflected reversely to the manner in which they are deflected, the normals to the surface of the reflector at points on the upper half of the directing curve. The second directing curve, which is on a cone, the axis of which 35 is coincident with the axis $y-y$ of the reflector and whose vertex is in the plane which contains the first directing curve, also has such geometrical characteristics that the normals to the surface of the reflector, at points on the lower half of the directing curve, are deflected reversely to the manner in which they are deflected, the normals to the 40 surface of the reflector at points on the upper half of the directing curve. It should be understood that all sections of the reflector and directing curves below the horizontal plane, passing through the axis of the reflector, in the terminology here used, 45 are considered the "lower half," and all sections of the reflector and directing curves above said horizontal plane are termed the "upper half" of the reflector or directing curves. Now by passing conics through 50 these two directing curves there will be

obtained such characteristics in the reflector that the result is the same kind of illumination and the same character of lighting effects, regardless of whether or not the light source is in the rear or the forward part of 55 the reflector. The best result is believed to be obtained by passing through these two directing curves, conics with a fixed focal point and a common axis, and such design is shown in the drawings. There will be conditions which make it desirable, or in fact necessary, to use conics of varying eccentricities with fixed or varying foci, either independently or together, one with the other. Those conditions which will impose 60 such variations will hereinafter be discussed.

It will, of course, be seen in my preferred form, that one directing curve is in a vertical plane passing through the focus of the 65 reflector, while the other directing curve is on the surface of a cone, yet the same result may be substantially or nearly obtained when both directing curves are predetermined on the surfaces of cones, or when both 70 directing curves are predetermined in vertical planes.

The reflecting surface illustrated diagrammatically in Figs. 1 to 8, inclusive, is, as 75 follows:

The reflecting surface generated and now to be considered has two directing curves, to wit: one shown in Fig. 1, indicated by c^1 and the second curve shown in Fig. 1 indicated by c^2 . Curve c^1 is taken in a plane 80 through the focus perpendicular to the axis, and the curve c^2 is taken on a cone of 60 degree vertex angle, the vertex of the cone being at the focus a .

In the description of the two directing curves c^1 and c^2 , the fact must be remembered that the axis of the cone upon which one of the directing curves is designed, and the axis $y-y$ of the reflector, and the axis of the generating conic, are all one and the same, and that the generating conic has a fixed focal center which is at the pre-determined point a on the axis $y-y$ of the reflector. The axis $y-y$ of the reflector also contains the center of the directing curve c^1 , 100 on which center the radius of the directing curve c^1 rotates.

The curve c^1 is taken in a plane perpendicular to the axis $y-y$ of the reflector, said plane passing through the fixed focus of the generating conic. The curve c^1 is a compound spiral curve so designed that the angle, between the radius of, and the normal to the curve, increases in arithmetical progression, per angle of rotation of the radius of the directing curve c^1 , as said radius rotates in either direction downwardly, from its uppermost vertical position to the horizontal plane of the axis $y-y$. The 115 said angle, between the radius of, and the 120

normal to the curve c^1 , decreases in the reverse order of said arithmetical progression, per angle of rotation of the radius of the directing curve c^1 as the said radius rotates in either direction downwardly from the horizontal plane of the axis $y-y$ to its lowermost vertical position; or stated in another way, the said angle, between the radius of, and the normal to the curve c^1 , increases arithmetically, per angle of rotation, as the axial radial plane of the reflector revolves in either direction downwardly from its uppermost position to the horizontal plane of the axis $y-y$, and also, said angle, between the radius of, and the normal to the curve c^1 , increases in the same arithmetical progression, per angle of rotation, as the axial radial plane of the reflector revolves in either direction upwardly from its lowermost vertical position to the horizontal plane of the axis $y-y$. The curve c^1 is continuous and unbroken and is symmetrical in respect to the vertical axial plane of the reflector.

From statements already made it is seen that any radial plane of the reflector contains a radius of the directing curve c^1 , a radius of the directing curve c^2 , and the axis $y-y$ of the reflector, said axis being the axis of revolution of the radial planes of the reflector.

The curve c^1 , Fig. 1, is so designed that the angle between the radius of, and the normal to the curve, is one-fifth of the angle of rotation of the radial plane of the reflector, in revolving from its uppermost position, downwardly to the horizontal plane of the axis $y-y$, and, reversely, the angle between the radius of, and the normal to the curve, is one-fifth of the angle of rotation of the radial plane of the reflector, in revolving upwardly from its lower vertical position to said horizontal plane. To illustrate: after rotating downwardly the radius of the curve c^1 30 degrees from zero or its upper vertical position, the angle between the radius of, and the normal to the curve c^1 , is 6 degrees; after 60 degrees similar rotation of the radius of the curve c^1 , the angle between the radius of, and the normal to the curve c^1 is 12 degrees; and after 90 degrees, similar rotation of the radius of the curve c^1 , the angle between the radius of, and the normal to the curve c^1 is 18 degrees; and, reversely, after rotating upwardly the radius of the curve c^1 30 degrees from its lower vertical position, the angle between the radius of, and the normal to the curve c^1 , is 6 degrees; after 60 degrees similar rotation upwardly of the radius of the curve c^1 , the angle between the radius of, and the normal to the curve c^1 , is 12 degrees; and after 90 degrees similar rotation upwardly of the radius of the curve c^1 , to wit: at the horizontal plane of the axis $y-y$,

the angle between the radius of, and the normal to the curve c^1 is 18 degrees. In Fig. 1, the normals to the curve c^1 are indicated by fine unbroken lines marked n , the radii being shown by broken lines b , which lines b also represent the radii of the reflector.

The statement above made is a specific illustration of what is meant by the statement that there are reverse progressions in the change of the angle between the normal to, and the radius of the directing curve, in the top and bottom, or in the upper and lower parts, of the reflector.

The values of the angles for the rotation of the axial radial plane of the reflector, are shown outside of the curve c^1 , in Fig. 1; and the values of the angles between the radii of, and the normals to the curve c^1 are shown within the curve c^1 in Fig. 1. It will be noted that, throughout the rotation of the radius of the curve c^1 from top to bottom, the said normals are on the undersides of the respective radii, or stated in another way, when a normal to the curve c^1 and a radius of the curve c^1 intersect at a point of the curve c^1 , then the said normal is under the said radius and makes an angle with the said radius. The above sentence explains what is meant by an angle between a normal to, and a radius of a curve; in other words, an angle between a radius and its normal to a curve, or an angle between a radius of, and a normal to a curve.

In Fig. 1, the angles between the normals to, and the radii of the curve c^1 , are marked on one side only of the vertical plane through the axis, but it will be understood that in a bi-symmetrical reflector, such as illustrated in the drawings, the angles will be the same for corresponding positions on both sides.

The second directing curve c^2 is a space curve on the surface of a cone whose axis is coincident with the axis $y-y$ of the reflector and the vertex of said cone is on the axis of the reflector at the point a , where the axis pierces the plane of the curve c^1 , said point a , being the fixed focus of the generating conic. The angle between the axis of the said cone and the elements thereof is 30 degrees in the drawings. The said curve c^2 , being a space curve, is shown in end elevation in Figs. 1 and 7. The radial distances of the points of the curve c^2 as they appear in Fig. 7, are equal to the true perpendicular distances of the respective points of the space curve c^2 from the axis $y-y$.

In Fig. 6, the space curve c^2 is shown in side elevation. In Fig. 6, the length on the element of the cone, from the vertex a to that point of the curve c^2 which is in the upper vertical axial plane of the reflector, is taken an assumed definite length, from a to 1, and the lengths of all of the other ele-

ments of the cone from the vertex a to the curve c^2 are determined in such manner that the angle between the normal to, and the radius of the curve c^2 in Fig. 7, which is an end elevation of the space curve c^2 , increases in arithmetical progression, per angle of rotation of the axial radial plane of the reflector as said axial radial plane revolves in either direction downwardly from its uppermost vertical position to the horizontal plane of the axis $y-y$, and said angle between the normal to, and the radius of the curve c^2 , Fig. 7, increases in the same arithmetical progression, per angle of rotation of the axial radial plane of the reflector as said axial radial plane revolves in either direction upwardly from its lowermost vertical position to the horizontal plane of the axis $y-y$.

20 The curve c^2 , Fig. 7, is so designed that the angle between the radius of, and the normal to the curve c^2 , Fig. 7, is one-fifth of the angle of rotation of the axial radial plane of the reflector, in revolving from its upper vertical position downwardly to the horizontal plane of the axis $y-y$, and, reversely, the angle between the radius of, and the normal to the curve c^2 , Fig. 7, is one-fifth of the angle of rotation of the axial radial plane of the reflector, in revolving upwardly from its lower vertical position to said horizontal plane of the axis $y-y$. To illustrate: after rotating downwardly the radius of the curve c^2 , Fig. 7, thirty degrees from zero or its upper vertical position, the angle between the radius of, and the normal to the curve c^2 , Fig. 7, is 6 degrees; after 60 degrees, rotation downwardly of the radius of the curve c^2 , Fig. 7, the angle between the radius of, and the normal to the curve c^2 , Fig. 7, is 12 degrees; and after 90 degrees rotation downwardly of the radius of the curve c^2 , Fig. 7, the angle between the radius of, and the normal to the curve c^2 , Fig. 7, is 18 degrees; and, reversely, after rotating upwardly the radius of the curve c^2 , Fig. 7, 30 degrees from its lower vertical position, the angle between the radius of, and the normal to the curve c^2 , Fig. 7, is 6 degrees; after 60 degrees rotation upwardly of the radius of the curve c^2 , Fig. 7, the angle between the radius of, and the normal to the curve c^2 , Fig. 7, is 12 degrees; and after 90 degrees rotation upwardly of the radius of the curve c^2 , Fig. 7, to wit: at the horizontal plane of the axis $y-y$, the angle between the radius of, and the normal to the curve c^2 , Fig. 7, is 18 degrees. In Fig. 7, the normals to the curve c^2 are indicated by the fine unbroken lines marked N , the radii of the curve c^2 , being shown by broken lines b .

The values of the angles for the rotation of the axial radial plane of the reflector, in Fig. 7, are shown inside of the dotted base

of the cone, and the values of the angles between the radii of, and the normals to the curve c^2 , Fig. 7, are shown just outside of the view of curve c^2 .

It will be further noted that throughout said rotation from top to bottom, the normals are on the undersides of the radii, or stated in another way, when a normal to the curve c^2 , Fig. 7 and a radius of the curve c^2 , Fig. 7 intersect at a point of the curve c^2 , Fig. 7, then the said normal is under the said radius.

In Fig. 7, the angles between the normals to, and the radii of the curve c^2 are marked on one side only of the vertical plane through the axis, but it will be understood that in a bi-symmetrical reflector, such as illustrated in the drawings, the angles will be the same for corresponding positions on both sides of the vertical plane through the axis of the reflector. The curve c^2 , as shown in Fig. 7, is continuous and unbroken.

The true lengths on the elements of the cone from the vertex to the curve c^2 , Fig. 6, are shown in Fig. 8. Fig. 8 is a development of the directing curve c^2 shown in side elevation in Fig. 6. The end elevation of the directing curve c^2 shown in Fig. 7, is also shown at c^2 in Fig. 1. The lengths on the elements of the cone from the vertex to certain curve c^2 , in the axial radial sections of the reflector, are also shown in Figs. 2, 3 and 4.

The two directing curves, in themselves, may, or will determine the eccentricity or the change of eccentricity of the generating conic of the reflecting surface, as will hereinafter be described. If the two directing curves c^1 and c^2 have the same ratio of variation in their radial distances, to wit: the perpendicular distances from corresponding points on the curves to the axis of the reflector, and if the generating conic has a fixed axis and a fixed focus, and if the axis of the cone is coincident with the fixed axis of the generating conic, and if the vertex of the cone is at the fixed focus of the generating conic, then the generating conic will have a constant eccentricity. The two directing curves c^1 and c^2 illustrated in Figs. 1, 6 and 7, have the characteristics just stated.

In the reflector as described above, the reflecting surface may be obtained by drawing through every two corresponding points on the two directing curves, c^1 and c^2 , (the two said points being situated in one and the same axial radial plane of the reflector) a conic whose focus is at a and whose axis is coincident with the axis $y-y$ of the reflector.

The curve c^2 , Fig. 1, is an end elevation of the intersection of the reflecting surface generated, with a 120 degree cone, or a cone whose elements are 60 degrees to the axis of the reflector, the axis of said cone is coincident with the axis of the reflector, the ver-

tex of said cone is at a , the fixed focus of the generating conic. Elements of this cone are also shown in Figs. 2, 3 and 4. The reflecting surface obtained from the two 5 directing curves c^1 , a plane curve, and c^2 , a space curve, may be obtained from two directing space curves, that is, one on a cone of a given angle and another on a second cone of a different angle, but having the 10 same vertex and the same axis as the first cone, the method employed in determining the direct curves on the cones being analogous to that described for the determination of the curve c^2 , the axes of the cones being 15 coincident with the fixed axis of the generating conic, to wit: the axis of the reflector.

The curve c^4 at the rim of the reflector is 20 determined by the mode of generation of the reflecting surface and the angle and the place at which the plane of the rim intersects the axis $y-y$ of the generated reflecting surface. In Figs. 1 to 5, inclusive, the rim of the reflector is shown as in a plane that intersects the axis $y-y$ at a right angle.

25 As above stated, the characteristics of the two directing curves may, or will, determine the eccentricity of the generating conic in each axial radial plane of the reflector.

The directing curves are in all cases, 30 continuous, that is, unbroken curves which are symmetrical in respect to the vertical plane through the axis of the reflector. The radii of said curves are in all cases understood to mean the perpendicular distances of the 35 points of the curve from the axis of the reflector.

The ratio of the angle between the radius 40 of, and the normal to the directing curve (contained in the plane perpendicular to the axis), in respect to the angle of rotation of the axial radial plane of the reflector, may be taken any desired value, and the said ratio may be greater than, equal to, or less than the ratio of the angle between the radius 45 of, and the normal to the curve (which is a projection of the directing curve on the cone, onto a plane perpendicular to its axis), in respect to the angle of rotation of the axial radial plane of the reflector.

50 The reflecting surface may be obtained by drawing conics through every two corresponding points of two directing curves selected from the various types of directing curves previously mentioned, the said two 55 corresponding points being situated in one and the same axial radial plane of the reflector. All of the conics passing through the said two corresponding points of the directing curves, have a common axis which is 60 coincident with the axis of the cone and the axis of the reflector.

If all of the conics have a common focus 65 which was predetermined at a fixed point on the said common axis of the conics, then the two above described directing curves will

determine the eccentricity of the conics. However, if all of the conics have a constant eccentricity, then the two above described directing curves will determine the position, along the common axis of the conics, of the 70 foci of the respective conics. Said axis is also the axis of the cone and the axis of the reflector, in all reflectors designed in accordance with the above described mode of generation. 75

It is a well known fact that automobiles make about ninety per cent of their mileage in the immediate vicinity of the home of the owner of the car, and that almost all cars delivered by manufacturers to a local agent will be sold to the consumers who live in that vicinity. It follows that cars sold by the particular local agent will be used almost exclusively in that territory. 80

The manufacturer knowing these facts 85 will, in many instances, slightly modify the design of the reflector to meet the conditions under which the car to which the reflectors are to be applied, is to be generally used. For instance, head lights to be used 90 on cars in Arizona, where roads are sandy and light in color, should be of somewhat different design from headlights to be used on cars that are to be run chiefly in 95 large cities where dark oiled roads are encountered.

It is well known that in symmetrical reflectors as at present used, all of the reflected light from one half thereof is projected above the road surface, while all reflected light from the other half of the reflector reaches the surface of the road, with a result that per unit of area, there will be less light on the surface of the road than there will be on a vertical object above the road. 100 One of the objects of the present invention is to throw as much light, per unit of area, upon the road as is thrown upon a vertical object above the road. 105

Other conditions which make it necessary 110 or desirable to modify the design of the reflector may be stated as follows:

The power of the light source or bulb, which may vary greatly but will probably be about 40 C. P. for average purposes. 115

The weight of the car; it being understood that light cars, such as Fords, will when overloaded sag at the rear more than heavy cars.

The color of the road, that is, dark roads such as oiled roads and light roads such as sandy roads. 120

Local atmospheric conditions, such as generally prevailing, clear or cloudy atmosphere. 125

Shifting of the light source caused by warping of the filament of the light bulb or the moving of the carbon electrode of an arc lamp.

Design of the filament, to wit, vertically 130

extended filament, horizontally extended filament, obliquely extended filament, conical filament, cylindrical filament and circular filament.

5. Nature of the roads, to wit, whether the majority of the roads of a particular district are level or undulating, quite straight or circuitous.

Desired distribution of light beam; for 10 narrow roads or wide roads, for short beam projection or for long beam projection.

What I claim is:

1. A headlight set for approximately horizontal projection and comprising a reflector 15 and a light source therein, said reflector having a surface substantially corresponding to a surface generated by a conic revolved in a downward direction on the approximately horizontal axis of the conic 20 while increasing, at the same time, both its radial distance from said axis and the distance from said light source of its vertex or point of intersection with said axis, the major portion of the upper part of said surface 25 being the reverse of the corresponding major portion of the lower part of said surface.

2. A headlight set for approximately horizontal projection and comprising a reflector 30 and a light source therein, a material portion of the reflector having a surface substantially corresponding to a surface generated by a conic revolved in a downward direction on the approximately horizontal axis of the conic while increasing the distance from said light source of its vertex or point of intersection with said axis, and the vertices or points of intersection with said axis of the curves of the lower portion of 40 the reflector being at greater distances from said light source than the vertices or points of intersection with said axis of the curves of the upper portion of the reflector, the lower part of said surface being the reverse 45 of the upper part of said surface.

3. A reflector having a reflecting surface substantially corresponding to a surface generated by a conic revolved downwardly on the approximately horizontal axis of said conic, said conic being guided in its revolution by a directing line so designed that when said directing line is projected on to a plane which is substantially perpendicular to said approximately horizontal axis, the resulting projection is a plane figure, the lower portion of which is a constant percentage of its upper portion.

4. A headlight set for approximately horizontal projection and comprising a reflector 60 and a light source therein, said reflector having a surface substantially corresponding to a surface generated by a conic revolved in a downward direction on the approximately horizontal axis of the conic 65 while increasing the distance from said light

source of its vertex or point of intersection with said axis, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure which has upper 70 segments and lower segments whose radii pass through and rotate on the point of intersection of said approximately horizontal axis with said plane, and for and throughout successive fractional parts of 75 the total angle of the downward rotation of the radius of an upper segment there are accompanying increases of the angle between the radius and its normal to said upper segment, which increases of said latter angle are substantially constant percentages 80 respectively of the increases of the angle between the radius and its normal to a lower segment, which latter increases occur for and throughout like and corresponding fractional parts of the total angle of the upward 85 rotation of the radius of said lower segment.

5. A headlight set for approximately horizontal projection and comprising a reflector 90 and a light source therein, said reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure which has upper 100 segments and lower segments whose radii pass through and rotate on the point of intersection of said approximately horizontal axis with said plane, and for and throughout successive fractional parts of 105 the total angle of the downward rotation of the radius of an upper segment there are accompanying increases of the angle between the radius and its normal to said upper segment, which increases of said latter angle are substantially constant percentages 110 respectively of the increases of the angle between the radius and its normal to a lower segment, which latter increases occur for and throughout like and corresponding fractional parts of the total angle of the upward rotation of the radius of said lower segment.

6. A headlight set for approximately horizontal projection and comprising a reflector and a light source therein, a material portion of the reflector having a surface substantially corresponding to a surface generated by a conic revolved in a downward direction on the approximately horizontal axis of the conic while increasing the distance from said light source of its vertex or point of intersection with said axis, and the vertices or points of intersection with said axis of the curves of the lower portion of the reflector being at greater distances from said light source than the vertices or points of intersection with said axis of the curves of the upper portion of the reflector, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure which has upper segments and lower segments whose radii pass through and rotate on the point of intersection of said approximately horizontal axis with said plane, and for and throughout successive fractional parts of the total angle of the downward rotation of the radius of an upper segment there are accompanying increases of the angle between the radius and its normal to said upper segment, which increases of said latter angle are substantially constant percentages respectively of the increases of the angle between the radius and its normal to a lower segment, which latter increases occur for and throughout like and corresponding fractional parts of the total angle of the upward rotation of the radius of said lower segment.

7. A headlight set for approximately horizontal projection and comprising a reflector and a light source therein, a material portion of the reflector having a surface substantially corresponding to a surface generated by a conic revolved in a downward direction on the approximately horizontal axis of the conic while increasing the distance from said light source of its vertex or point of intersection with said axis, and the radial distances from said axis of the curves of the lower portion of the reflector being greater than the radial distances from said axis of the curves of the upper portion of the reflector, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure which

has upper segments and lower segments whose radii pass through and rotate on the point of intersection of said approximately horizontal axis with said plane, and for and throughout successive fractional parts of the total angle of the downward rotation of the radius of an upper segment there are accompanying increases of the angle between the radius and its normal to said upper segment, which increases of said latter angle are substantially constant percentages respectively of the increases of the angle between the radius and its normal to a lower segment, which latter increases occur for and throughout like and corresponding fractional parts of the total angle of the upward rotation of the radius of said lower segment.

8. A headlight set for approximately horizontal projection and comprising a reflector and a light source therein, a material portion of the reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, and the vertices or points of intersection with said axis of the curves of the lower portion of the reflector being at greater distances from said light source than the vertices or points of intersection with said axis of the curves of the upper portion of the reflector, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure which has upper segments and lower segments whose radii pass through and rotate on the point of intersection of said approximately horizontal axis with said plane, and for and throughout successive fractional parts of the total angle of the downward rotation of the radius of an upper segment there are accompanying increases of the angle between the radius and its normal to said upper segment, which increases of said latter angle are substantially constant percentages respectively of the increases of the angle between the radius and its normal to a lower segment, which latter increases occur for and throughout like and corresponding fractional parts of the total angle of the upward rotation of the radius of said lower segment.

9. A headlight set for approximately horizontal projection and comprising a reflector and a light source therein, a material

- portion of the reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, and the radial distances from said axis of the curves of the lower portion of the reflector being greater than the radial distances from said axis of the curves of the upper portion of the reflector, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure which has upper segments and lower segments whose radii pass through and rotate on the point of intersection of said approximately horizontal axis with said plane, and for and throughout successive fractional parts of the total angle of the downward rotation of the radius of an upper segment there are accompanying increases of the angle between the radius and its normal to said upper segment, which increases of said latter angle are substantially constant percentages respectively of the increases of the angle between the radius and its normal to a lower segment, which latter increases occur for and throughout like and corresponding fractional parts of the total angle of the upward rotation of the radius of said lower segment.
10. A headlight set for approximately horizontal projection and comprising a reflector and a light source therein, said reflector having a surface substantially corresponding to a surface generated by a conic revolved in a downward direction on the approximately horizontal axis of the conic while varying, at the same time, both its radial distance from said axis and the distance from said light source of its vertex or point of intersection with said axis, and the radial distances from said axis of the conics of the terminal portions of the surface thus generated being greater than the radial distances from said axis of the conics of the initial portions of the surface thus generated, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure which has upper segments and lower segments whose radii pass through and rotate on the point of intersection of said approximately horizontal axis with said plane, and for and throughout successive fractional parts of the total angle of the downward rotation of the radius of an upper segment there are accompanying increases of the angle between the radius and its normal to said upper segment, which increases of said latter angle are substantially constant percentages respectively of the increases of the angle between the radius and its normal to a lower segment, which latter increases occur for and throughout like and corresponding fractional parts of the total angle of the upward rotation of the radius of said lower segment.
11. A headlight set for approximately horizontal projection and comprising a reflector and a light source therein, said reflector having a surface substantially corresponding to a surface generated by a conic revolved in a downward direction on the approximately horizontal axis of the conic while varying, at the same time, both its radial distance from said axis and the distance from said light source of its vertex or point of intersection with said axis, and the radial distances from said axis of the conics of the terminal portions of the surface thus generated being greater than the radial distances from said axis of the conics of the initial portions of the surface thus generated, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure which has upper segments and lower segments whose radii pass through and rotate on the point of intersection of said approximately horizontal axis with said plane, and for and throughout successive fractional parts of the total angle of the downward rotation of the radius of an upper segment there are accompanying increases of the angle between the radius and its normal to said upper segment, which increases of said latter angle are substantially constant percentages respectively of the increases of the angle between the radius and its normal to a lower segment, which latter increases occur for and throughout like and corresponding fractional parts of the total angle of the upward rotation of the radius of said lower segment.
12. A headlight set for approximately horizontal projection and comprising a reflector and a light source therein, said reflector having its entire surface substantially corresponding to a surface generated by a conic revolved downwardly, in opposite

directions, on the approximately horizontal axis of the conic while continuously increasing the distance from said light source of its vertex or point of intersection with said 5 axis, said conic being guided in its revolution by passing through successive points of a directing line so designed that when said directing line is projected onto a plane which is substantially perpendicular to said 10 approximately horizontal axis, by means of lines parallel to said approximately horizontal axis, the resulting projection is a plane figure which has upper segments and lower segments whose radii pass through 15 and rotate on the point of intersection of said approximately horizontal axis with said plane, and for and throughout successive fractional parts of the total angle of the downward rotation of the radius of an upper 20 segment there are accompanying increases of the angle between the radius and its normal to said upper segment, which increases of said latter angle are substantially constant percentages respectively of 25 the increases of the angle between the radius and its normal to a lower segment, which latter increases occur for and throughout like and corresponding fractional parts of the total angle of the upward rotation of the 30 radius of said lower segment.

13. A headlight set for approximately horizontal projection and comprising a reflector and a light source therein, said reflector having its entire surface substantially corresponding to a surface generated by a conic revolved downwardly, in opposite directions, on the approximately horizontal axis of the conic while continuously increasing, at the same time, both its radial 40 distance from said axis and the distance from said light source of its vertex or point of intersection with said axis, said conic being guided in its revolution by passing through successive points of a directing line so designed that when said directing 45 line is projected onto a plane which is substantially perpendicular to said approximately horizontal axis, by means of lines parallel to said approximately horizontal axis, the resulting projection is a plane figure which has upper segments and lower segments whose radii pass through and rotate on the point of intersection of said approximately horizontal axis with said plane, and for and throughout successive fractional parts of the total angle of the downward rotation of the radius of an upper segment there are accompanying increases of the angle 50 between the radius and its normal to said upper segment, which increases of said latter angle are substantially constant percentages respectively of the increases of the angle between the radius and its normal to a lower segment, which latter increases occur for and throughout like and corresponding fractional parts of the total angle of the upward rotation of the radius of 55 said lower segment.

14. A headlight set for approximately horizontal projection and comprising a reflector and a light source therein, the surface of said reflector substantially corresponding to a surface generated by a conic revolved downwardly, on the approximately horizontal axis of the conic while continuously increasing its radial distance from said axis, and the vertices or points of intersection with said axis of the conics of the lower portion of the reflector thus generated being at greater distances from 70 said light source than the vertices or points of intersection with said axis of the conics of the upper portion of the reflector thus generated, said conic being guided in its revolution by passing through successive 75 points of a directing line so designed that when said directing line is projected onto a plane which is substantially perpendicular to said approximately horizontal axis, by means of lines parallel to said approximately horizontal axis, the resulting projection is a plane figure which has upper segments and lower segments whose radii pass through and rotate on the point of 80 intersection of said approximately horizontal axis with said plane, and for and throughout successive fractional parts of the total angle of the downward rotation of the radius of an upper segment there are accompanying increases of the angle between the radius and its normal to said upper segment, which increases of said latter angle are substantially constant percentages respectively of the increases of the angle between the radius and its normal to a lower segment, which latter increases occur for and throughout like and corresponding fractional parts of the total angle of the upward rotation of the radius of 85 said lower segment.

15. A headlight set for approximately horizontal projection and comprising a reflector and a light source therein, said reflector having a surface substantially corresponding to a surface generated by a conic revolved in a downward direction on the approximately horizontal axis of the conic while increasing the distance from said light source of its vertex or point of intersection with said axis, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion 95

- of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.
16. A headlight set for approximately horizontal projection and comprising a reflector and a light source therein, said reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.
17. A headlight set for approximately horizontal projection and comprising a reflector and a light source therein, a material portion of the reflector having a surface substantially corresponding to a surface generated by a conic revolved in a downward direction on the approximately horizontal axis of the conic while increasing the distance from said light source of its vertex or point of intersection with said axis, and the radial distances from said axis of the curves of the lower portion of the reflector being at greater distances from said light source than the vertices or points of intersection with said axis of the curves of the upper portion of the reflector, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.
18. A headlight set for approximately horizontal projection and comprising a reflector and a light source therein, a material portion of the reflector having a surface substantially corresponding to a surface generated by a conic revolved in a downward direction on the approximately horizontal axis of the conic while increasing the distance from said light source of its vertex or point of intersection with said axis, and the radial distances from said axis of the curves of the lower portion of the reflector being greater than the radial distances from said axis of the curves of the upper portion of the reflector, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the point of intersection of said approximately horizontal axis.

with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

19. A headlight set for approximately horizontal projection and comprising a reflector and a light source therein, a material portion of the reflector having a surface substantially corresponding to a surface generator by a conic revolved in a downward direction on the approximately horizontal axis of the conic while increasing, at the same time, both its radial distance from said axis and the distance from said light source of its vertex or point of intersection with said axis, and the vertices or points of intersection with said axis of the curves of the lower portion of the reflector being at greater distances from said light source than the vertices or points of intersection with said axis of the curves of the upper portion of the reflector, said conic being guided in its revolution by passing through successive points of a directing line so designed that when said directing line is projected onto a plane which is substantially perpendicular to said approximately horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle, of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

10 horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

20. A headlight set for approximately horizontal projection and comprising a reflector and a light source therein, a material portion of the reflector having a surface substantially corresponding to a surface gen-

erated by a conic revolved in a downward direction on the approximately horizontal axis of the conic while increasing, at the same time, both its radial distance from said axis and the distance from said light source of its vertex or point of intersection with said axis, and the radial distances from said axis of the curves of the lower portion of the reflector being greater than the radial distances from said axis of the curves of the upper portion of the reflector, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle, of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

21. A headlight set for approximately horizontal projection and comprising a reflector and a light source therein, said reflector having a surface substantially corresponding to a surface generated by a conic revolved in a downward direction on the approximately horizontal axis of the conic while varying, at the same time, both its radial distance from said axis and the distance from said light source of its vertex or point of intersection with said axis, and the radial distances from said axis of the conics of the terminal portions of the surface thus generated being greater than the radial distances from said axis of the conics of the initial portions of the surface thus generated, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major

portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

22. A headlight set for approximately horizontal projection and comprising a reflector and a light source therein, said reflector having a surface substantially corresponding to a surface generated by a conic revolved in a downward direction on the approximately horizontal axis of the conic while varying the distance from said light source of its vertex or point of intersection with said axis, and the vertices or points of intersection with said axis of the conics of the terminal portions of the surface thus generated being at greater distances from said light source than the vertices or points of intersection with said axis of the conics of the initial portions of the surface thus generated, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

24. A headlight set for approximately horizontal projection and comprising a reflector and a light source therein, said reflector having its entire surface substantially corresponding to a surface generated by a conic revolved downwardly, in opposite directions, on the approximately horizontal axis of the conic while continuously increasing, at the same time, both its radial distance from said axis and the distance from said light source of its vertex or point of intersection with said axis, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

23. A headlight set for approximately horizontal projection and comprising a reflector and a light source therein, said re-

flector having its entire surface substantially corresponding to a surface generated by a conic revolved downwardly, in opposite directions, on the approximately horizontal axis of the conic while continuously increasing the distance from said light source of its vertex or point of intersection with said axis, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle of the downward rotation of the radius of the upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

24. A headlight set for approximately horizontal projection and comprising a reflector and a light source therein, said reflector having its entire surface substantially corresponding to a surface generated by a conic revolved downwardly, in opposite directions, on the approximately horizontal axis of the conic while continuously increasing, at the same time, both its radial distance from said axis and the distance from said light source of its vertex or point of intersection with said axis, said conic being guided in its revolution by passing through successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said upper seg-

ment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

25. A headlight set for approximately horizontal projection and comprising a reflector and a light source therein, the surface of said reflector substantially corresponding to a surface generated by a conic revolved downwardly, on the approximately horizontal axis of the conic while continuously increasing its radial distance from said axis, and the vertices or points of intersection with said axis of the conics of the lower portion of the reflector thus generated being at greater distances from said light source than the vertices or points of intersection with said axis of the conics of the upper portion of the reflector thus generated, said conic being guided in its revolution by passing through successive points of a directing line so designed that when said 30 directing line is projected onto a plane which is substantially perpendicular to said approximately horizontal axis, by means of lines parallel to said approximately horizontal axis, the resulting projection is a plane figure having an upper segment and a lower segment which together constitute the major portion of said plane figure and the radii of said segments pass through and rotate on the 35 point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the 40 angle between the radius and its normal to said lower segment, which latter increases occur for and throughout all the like and corresponding fractional parts of the total angle of the upward rotation of the radius of said lower segment.

50. A headlight set for approximately horizontal projection and comprising a reflector and a light source therein, said reflector having a surface substantially corresponding to a surface generated by a conic revolved in a downward direction on the approximately horizontal axis of the conic while increasing the distance from said light source of its vertex or point of intersection

55. with said axis, said conic being guided in its revolution by passing through the successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of 60 said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of 65 said latter angle are substantially constant percentages respectively of the increases of the angle between the radius and its normal to said lower segment, which latter increases occur for and throughout all the like and 70 corresponding fractional parts of the total angle of the upward rotation of the radius of said lower segment.

75. 27. A headlight set for approximately horizontal projection and comprising a reflector and a light source therein, said reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, said conic being guided in its revolution by passing through the successive points of a directing line so designed that when said directing line is projected onto a plane which is substantially perpendicular to said approximately horizontal axis, by means of 80 lines parallel to said approximately horizontal axis, the resulting projection is a plane figure having an upper segment and a lower segment which together constitute substantially the entire portion of said plane figure and the radii of said segments pass through and rotate on the point of intersection of said approximately horizontal axis with said plane, and for and throughout 85 all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and 90 corresponding fractional parts of the total angle of the upward rotation of the radius of said lower segment.

95. 28. A headlight set for approximately horizontal projection and comprising a reflector and a light source therein, said reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, said conic being guided in its revolution by passing through the successive points of a directing line so designed that when said directing line is projected onto a plane which is substantially perpendicular to said approximately horizontal axis, by means of 100 lines parallel to said approximately horizontal axis, the resulting projection is a plane figure having an upper segment and a lower segment which together constitute substantially the entire portion of said plane figure and the radii of said segments pass through and rotate on the point of intersection of said approximately horizontal axis with said plane, and for and throughout 105 all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and 110 corresponding fractional parts of the total angle of the upward rotation of the radius of said lower segment.

115. 29. A headlight set for approximately horizontal projection and comprising a reflector and a light source therein, said reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, said conic being guided in its revolution by passing through the successive points of a directing line so designed that when said directing line is projected onto a plane which is substantially perpendicular to said approximately horizontal axis, by means of 120 lines parallel to said approximately horizontal axis, the resulting projection is a plane figure having an upper segment and a lower segment which together constitute substantially the entire portion of said plane figure and the radii of said segments pass through and rotate on the point of intersection of said approximately horizontal axis with said plane, and for and throughout 125 all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

lower segment, which latter increases occur for and throughout all the like and corresponding fractional parts of the total angle of the upward rotation of the radius of said lower segment.

28. A headlight set for approximately horizontal projection and comprising a reflector and a light source therein, a material portion of the reflector having a surface substantially corresponding to a surface generated by a conic revolved in a downward direction on the approximately horizontal axis of the conic while increasing the distance from said light source of its vertex or point of intersection with said axis, and the vertices or points of intersection with said axis of the curves of the lower portion of the reflector being at greater distances from said light source than the vertices or points of intersection with said axis of the curves of the upper portion of the reflector, said conic being guided in its revolution by passing through the successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

29. A headlight set for approximately horizontal projection and comprising a reflector and a light source therein, a material portion of the reflector having a surface substantially corresponding to a surface generated by a conic revolved in a downward direction on the approximately horizontal axis of the conic while increasing the distance from said light source of its vertex or point of intersection with said axis, and the radial distances from said axis of the curves of the lower portion of the reflector being greater than the radial distances from said axis of the curves of the upper portion of

the reflector, said conic being guided in its revolution by passing through the successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

30. A headlight set for approximately horizontal projection and comprising a reflector and a light source therein, a material portion of the reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, and the vertices or points of intersection with said axis of the curves of the lower portion of the reflector being at greater distances from said light source than the vertices or points of intersection with said axis of the curves of the upper portion of the reflector, said conic being guided in its revolution by passing through the successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of said plane figure and the radii of said segments pass through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively of the increases of the angle between the radius and its normal to said lower segment, which latter increases occur for and throughout all the like and corresponding fractional parts of the total angle of the upward rotation of the radius of said lower segment.

segment there are accompanying increases of the angle between the radius and its normal to said upper segment, which increases of said latter angle are substantially constant 5 percentages respectively of the increases of the angle between the radius and its normal to said lower segment, which latter increases occur for and throughout all the like and corresponding fractional parts of the 10 total angle of the upward rotation of the radius of said lower segment.

31. A headlight set for approximately horizontal projection and comprising a reflector and a light source therein, a material 15 portion of the reflector having a surface substantially corresponding to a surface generated by a conic revolved in a downward direction on the approximately horizontal axis of the conic while increasing, at 20 the same time, both its radial distance from said axis and the distance from said light source of its vertex or point of intersection with said axis, and the radial distances from said axis of the curves of the lower 25 portion of the reflector being greater than the radial distances from said axis of the curves of the upper portion of the reflector, said conic being guided in its revolution by passing through the successive points of a 30 directing line so designed that when said directing line is projected onto a plane which is substantially perpendicular to said approximately horizontal axis, by means of lines parallel to said approximately horizontal axis, the resulting projection is a plane figure having an upper segment and a lower segment which together 35 constitute substantially the entire portion of said plane figure and the radii of said segments pass through and rotate on the point of intersection of said approximately horizontal axis with said plane, and for and throughout all the successive fractional parts of the total angle of the downward 40 rotation of the radius of said upper segment there are accompanying increases of the angle between the radius and its normal to said upper segment, which increases of said latter angle are substantially constant 45 percentages respectively of the increases of the angle between the radius and its normal to said lower segment, which latter increases occur for and throughout all the like and corresponding fractional parts of the 50 total angle of the upward rotation of the radius of said lower segment.

32. A headlight set for approximately horizontal projection and comprising a reflector and a light source therein, said reflector having a surface substantially corresponding to a surface generated by a conic revolved in a downward direction on the approximately horizontal axis of the conic while varying, at the same time, both its 55 radial distance from said axis and the dis-

tance from said light source of its vertex or point of intersection with said axis, and the radial distances from said axis of the conics of the terminal portions of the surface thus generated being greater than the 70 radial distances from said axis of the conics of the initial portions of the surface thus generated, said conic being guided in its revolution by passing through the successive points of a directing line so designed that when said directing line is projected onto a plane which is substantially perpendicular to said approximately horizontal axis, by means of lines parallel to said approximately horizontal axis, the resulting 75 projection is a plane figure having an upper segment and a lower segment which together constitute substantially the entire portion of said plane figure and the radii of said segments pass through and rotate on the point of intersection of said approximately horizontal axis with said plane, and for and throughout all the successive fractional parts of the total angle of the downward 80 rotation of the radius of said upper segment there are accompanying increases of the angle between the radius and its normal to said upper segment, which increases of said latter angle are substantially constant 85 percentages respectively of the increases of the angle between the radius and its normal to said lower segment, which latter increases occur for and throughout all the like and corresponding fractional parts of the 90 total angle of the upward rotation of the radius of said lower segment.

33. A headlight set for approximately horizontal projection and comprising a reflector and a light source therein, said reflector having a surface substantially corresponding to a surface generated by a conic revolved in a downward direction on the approximately horizontal axis of the conic while varying the distance from said light source of its vertex or point of intersection with said axis, and the vertices or 105 points of intersection with said axis of the conics of the terminal portions of the surface thus generated being at greater distances from said light source than the vertices or points of intersection with said axis of the conics of the initial portions of the surface thus generated, said conic being guided in its revolution by passing through the successive points of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of said plane figure and the radii of said segments pass through and 110

rotate on the point of intersection of said approximately horizontal axis with said plane, and for and throughout all the successive fractional parts of the total angle of 5 the downward rotation of the radius of said upper segment there are accompanying increases of the angle between the radius and its normal to said upper segment, which increases of said latter angle are 10 substantially constant percentages respectively of the increases of the angle between the radius and its normal to said lower segment, which latter increases occur for and throughout all the like and corresponding 15 fractional parts of the total angle of the upward rotation of the radius of said lower segment.

34. A headlight set for approximately horizontal projection and comprising a reflector and a light source therein, said reflector having its entire surface substantially corresponding to a surface generated by a conic revolved downwardly, in opposite directions, on the approximately horizontal 20 axis of the conic while continuously increasing the distance from said light source of its vertex or point of intersection with said axis, said conic being guided in its revolution by passing through the successive points 25 of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of said plane figure and the radii of said segments pass 30 through and rotate on the point of intersection of said approximately horizontal axis with said plane, and for and throughout all the successive fractional parts of the total angle of the downward rotation of the 35 radius of said upper segment there are accompanying increases of the angle between the radius and its normal to said upper segment, which increases of said latter angle are substantially constant percentages respectively 40 of the increases of the angle between the radius and its normal to said lower segment, which latter increases occur for and throughout all the like and corresponding fractional parts of the total angle of the 45 upward rotation of the radius of said lower segment.

35. A headlight set for approximately horizontal projection and comprising a reflector and a light source therein, said reflector having its entire surface substantially corresponding to a surface generated by a conic revolved downwardly, in opposite directions, on the approximately horizontal 50 axis of the conic while continuously increasing the distance from said light source of its vertex or point of intersection with said axis, said conic being guided in its revolution by passing through the successive points 55 of a directing line so designed that when said directing line is projected onto a plane which is substantially perpendicular to said approximately horizontal axis, the resulting projection is a plane figure having an upper segment and a lower segment which together constitute substantially the entire portion of said plane figure and the radii of said segments pass 60 through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively 65 of the increases of the angle between the radius and its normal to said lower segment, which latter increases occur for and throughout all the like and corresponding fractional parts of the total angle of the upward rotation of the radius of said lower segment.

36. A headlight set for approximately horizontal projection and comprising a reflector and a light source therein, said reflector having its entire surface substantially corresponding to a surface generated by a conic revolved downwardly, in opposite directions, on the approximately horizontal 70 axis of the conic while continuously increasing, at the same time, both its radial dis-

tance from said axis and the distance from said light source of its vertex or point of intersection with said axis, said conic being guided in its revolution by passing through the successive points of a directing line so 75 designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of said plane figure and the radii of said segments pass through and rotate on the point of intersection of said approximately horizontal axis with said plane, and for and throughout all the successive fractional parts of the total angle of the downward rotation of the radius of said 80 upper segment there are accompanying increases of the angle between the radius and its normal to said upper segment, which increases of said latter angle are substantially constant percentages respectively 85 of the increases of the angle between the radius and its normal to said lower segment, which latter increases occur for and throughout all the like and corresponding fractional parts of the total angle of the 90 upward rotation of the radius of said lower segment.

36. A headlight set for approximately horizontal projection and comprising a reflector and a light source therein, the surface of said reflector substantially corresponding to a surface generated by a conic revolved downwardly, on the approximately horizontal axis of the conic while continuously increasing its radial distance from 95 said axis, and the vertices or points of intersection with said axis of the conics of the lower portion of the reflector thus generated being at greater distances from said light source than the vertices or points of intersection with said axis of the conics of the upper portion of the reflector thus generated, said conic being guided in its revolution by passing through the successive points 100 of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of said plane figure and the radii of said segments pass 105 through and rotate on the point of intersection of said approximately horizontal axis with said plane, and for and throughout all the successive fractional parts of the total angle of the downward rotation of the radius of said upper segment there are accompanying increases of the angle between the radius and its normal to said upper segment, which increases of said latter angle are substantially constant percentages respectively 110 of the increases of the angle between the radius and its normal to said lower segment, which latter increases occur for and throughout all the like and corresponding fractional parts of the total angle of the upward rotation of the radius of said lower segment.

36. A headlight set for approximately horizontal projection and comprising a reflector and a light source therein, the surface of said reflector substantially corresponding to a surface generated by a conic revolved downwardly, on the approximately horizontal axis of the conic while continuously increasing its radial distance from 115 said axis, and the vertices or points of intersection with said axis of the conics of the lower portion of the reflector thus generated being at greater distances from said light source than the vertices or points of intersection with said axis of the conics of the upper portion of the reflector thus generated, said conic being guided in its revolution by passing through the successive points 120 of a directing line so designed that when said directing line is projected onto a plane which is substantially perpendicular to said approximately horizontal axis, by means of lines parallel to said approximately horizontal axis, the resulting projection is a plane figure having an upper segment and a lower segment which together constitute substantially the entire portion of said plane figure and the radii of said segments pass through and rotate on the point of intersection of said approximately horizontal axis with said plane, and for and throughout all the successive fractional parts of the total angle of the downward rotation of the radius of said upper segment there are ac- 125

companying increases of the angle between the radius and its normal to said upper segment, which increases of said latter angle are substantially constant percentages respectively of the increases of the angle between the radius and its normal to said lower segment, which latter increases occur

for and throughout all the like and corresponding fractional parts of the total angle of the upward rotation of the radius of said 10 lower segment.

In testimony whereof I affix my signature.

OVERTON WINSTON.
